UNITED STATES PATENT OFFICE.

JAMES M. BUTCHER, OF CHICAGO, ILLINOIS, ASSIGNOR TO SENTINEL ALARM CO., OF CHICAGO, ILLINOIS, A CORPORATION OF ILLINOIS.

ALARM.

1,398,585.

Specification of Letters Patent.

Patented Nov. 29, 1921.

Application filed February 16, 1920. Serial No. 358,848.

To all whom it may concern:

Be it known that I, JAMES M. BUTCHER, a citizen of the United States, residing at Chicago, in the county of Cook and State of Illinois, have invented certain new and useful Improvements in Alarms, of which the following is a specification.

This invention relates to an alarm adapted to be actuated or released by an external influence exerted upon its releasing member (usually in the form of a plunger), and particularly to that type of such alarms in which a control attachment is associated with the plunger for the purpose of producing in the alarm, at will, the so-called annunciator action in which ringing continues only so long as the external influence continues to displace the releasing member, or continuous ringing or alarm action in which the alarm when once released by the external influence can be arrested only by voluntary act of one having access to the alarm, as, for instance, by shifting the control attachment. An alarm device performing these general functions is disclosed and broadly claimed in my Letters Patent No. 1,327,021, issued January 6th, 1920.

The object of the present invention is to provide an improved construction of controlling attachment and other parts in an alarm of the character above described, whereby parts may be produced more cheaply without detracting from their efficiency or durability in use.

While an alarm having the features constituting the subject-matter of the present invention may be applied in various locations and through any one of a number of different mountings through which to impose the external influence that is to release the alarm, it will be herein shown, for purposes of illustration, as applied through means of a mounting adapted to coact with a door and a door jamb.

In the accompanying drawing—

Figure 1 is a face view of an alarm in which the features of the present invention may be embodied, together with a mounting therefor and a door with which it is associated.

Fig. 2 is a face view of the alarm with the bell removed.

Fig. 3 is a view similar to Fig. 2 with the main wheel and arbor removed to dis-

trolling attachment, these parts being in the position which leaves the duration of ringing under control of the external releasing influence.

Fig. 4 is a view similar to Figs. 2 and 3 with the vibrator elements removed and with the control attachment shifted to hold the releasing plunger in continuous ring position.

Fig. 4a is a detail view of the plunger spring shown in Fig. 4.

Fig. 5 is a face view of the alarm actuating spring and spring case with the base plate and operating mechanism removed; and

Fig. 6 is a side elevation of the alarm with the bell and the mounting in section.

1 represents a mounting which may be secured by screws 2 to a door or other object to which the alarm is to be applied, and which is provided with a key-hole slot 3 to receive a stud 4 of the alarm 5 in a manner to permit the alarm to be applied to and removed from the mounting at will.

The particular mounting here illustrated further comprises a thrust bar 6 having an end 7 adapted to coöperate with a member between which and the alarm relative movement takes place; also a presser-foot 8 adapted to act upon the plunger 9 for releasing the bell by movement of the thrust bar 6, and the thrust bar 6 is supported by an offset from the mounting 1 through the medium of a pair of parallel radius arms 10 flexible in the direction of movement of bar 6 and having inherent resiliency sufficient to develop releasing pressure on the plunger 9 when the end 7 of bar 6 is left unrestrained.

The parts thus far described constitute the subject-matter of a copending application executed by me of even date herewith and need not be further described herein.

As will be seen from Fig. 3, plunger 9 carries a dog 11 adapted to enter the toothed spaces of a star wheel 12, and is normally pushed into such engagement with the star wheel by means of the spring 13 having a bearing end 14 that presses beneath the offset 15 of the plunger 9. The star wheel 12 is under constant driving tension of the spring 16 (Fig. 5) exerted through the winding post 17, main wheel 18, and multiplying wheels 19, 20, and 21. Spring 13

is preferably a thin metal stamping having a reduced neck 13^a which adapts it to seat in a recess 22^a in the periphery of the base plate 22, in which recess the spring is confined by the shell 23 forming the wall of the spring chamber and within which the base plate 22 snugly fits.

The releasing plunger 9 if left in the position shown in Fig. 3 will remain depressed only so long as the external releasing influence continues, and will return to arrest the alarm as soon as such external influence ceases. In order to permit the alarm to be set for automatically retaining the plunger 15 9 in its depressed position when once it is pressed in by the external influence, said plunger has a shoulder 24 adapted to receive detent 25 on control lever 26 which presents a finger-piece 27 in convenient position for manipulation, and which is mounted for movement upon the arbor bearing 28 through the medium of a split friction sleeve 29 confined by main wheel 18 (Fig. 6) and which holds the lever 26 in 20 either of its two positions to which it may be adjusted. By appropriate pressure upon the finger-piece 27, detent 25 is introduced in position to encounter the shoulder 24 and prevent return of the plunger 9 under the 25 influence of spring 13. And in order that the controlling lever may be set in advance of the depression of plunger 9 the shoulder 24 is carried by the plunger 9 through the medium of a long resilient tongue 24^a that yields to the detent 25 when said detent is pressed against the tongue, but which restores the shoulder 24 to its normal path of movement, and therefore in position beneath the detent 25 as shown in Fig. 4, whenever 40 the plunger may happen to be depressed by an external condition to be guarded against.

Movement of lever 26 in the releasing direction may be limited by a stop 26^a, and said lever is preferably arrested in its plunger-controlling position by the contact of its end 26^b against the arbor bearing 19^a. Arbor bearings 19^a and 28 serve as guides for the plunger 9, which is appropriately slotted to fit over said bearings.

50 Spring 16 is connected at its driving end with the central arbor 17 which serves alike for receiving spring winding movement from the bell 5^a mounted on the outer end of said arbor, and for transmitting the spring drive to the train of wheels. The outer end of the spring has a fixed anchorage on a tongue 30 struck from the metal of the shell 23 and engaging a slot in the end of the spring.

60 By means of the controlling attachment above described, the alarm may be set by manipulating the finger-piece 27 to the right as viewed in the drawing and thereby leave the alarm free to automatically arrest

the ringing whenever the external operating influence ends, as, for instance, the closing of the door upon which the alarm is mounted, and in this way the alarm is adapted to serve as an annunciator. Or finger-piece 27 may be manipulated to the left to press the 70 detent 25 into the path of the shoulder 24, displacing said shoulder for the time being, so that whenever the plunger is pressed in by the opening of the door or other object upon which the alarm is mounted, the ringing of the alarm will continue until it runs down or until the finger-piece 27 is voluntarily shifted to the left.

I claim:

1. In an alarm device, a plunger having 80 an alarm-arresting position and an alarm-releasing position, and a control device movable into the path of the plunger to hold the plunger in the alarm-releasing position; said plunger having a shoulder through 85 which it engages the control device; and said shoulder being resiliently supported upon the plunger whereby it yields to the control device when the plunger is in alarm-arresting position and returns to engagement with the control device when the plunger is in alarm-releasing position.

2. In an alarm device, a plunger moving to release or arrest the alarm, a tongue carried by said plunger, and a movable detent 95 having a path of movement intersecting the path of said tongue to arrest the plunger; said tongue being resilient in the direction of movement of the detent to permit the detent to assume arresting position while the 100 tongue is across its path.

3. In an alarm device, a plunger for releasing and arresting the action of the alarm, an elongated resilient tongue carried by said plunger, extending in the direction 105 of the movement thereof, and presenting a shoulder through which to arrest the plunger, and a detent lever pivotally mounted upon the alarm, carrying a detent through which it intersects the path of the tongue, 110 and having an end presented for manipulation of the lever.

4. In an alarm device, a reciprocating alarm releasing member having a shoulder by which to retain it in alarm releasing position, and means controlling said member comprising a cylindrical bearing and a lever having a sleeve frictionally embracing said bearing and extending rigidly from said sleeve to an arc intersecting the path 120 of said shoulder; said shoulder being supported on said releasing member with rigidity in the direction of reciprocation of said member but with resiliency in the direction of said arc.

Signed at Chicago, Illinois, this 12th day of February, 1920.

JAMES M. BUTCHER,
